UNITED STATES PATENT OFFICE.

CHARLES H. CLARK, OF CLEVELAND, OHIO.

PAVEMENT-PLOW.

1,186,549.

Specification of Letters Patent. Patented June 13, 1916.

Application filed September 11, 1914. Serial No. 861,180.

To all whom it may concern:

Be it known that I, CHARLES H. CLARK, a citizen of the United States, residing at Cleveland, in the county of Cuyahoga and State of Ohio, have invented a certain new and useful Improvement in Pavement-Plows, of which the following is a full, clear, and exact description.

The rails comprising the tracks of street railways in cities are generally secured on wood ties; the opposite rails are connected by metal tie rods; a layer of sand is spread between the rails so as to be about an inch thick over the ties; stone paving blocks are laid upon this sand between the rails so that each tie rod lies between two transversely extended rows of said paving blocks; and finally asphalt or cement or some equivalent is poured into the interstices between the paving blocks, so as to firmly secure them together and prevent relative movement. Sometimes, also, a layer of concrete about an inch thick, more or less, is spread over the surface of said paving blocks. When it is desired to relay the tracks (and this is of more or less frequent occurrence) it is necessary to first remove the paving blocks from between the tracks, and then to disconnect the tie rods from the rails. Heretofore this work, preparatory to relaying tracks, has been done by manual labor, the laborers using picks, crowbars and the like to loosen the paving blocks, so that other men can pick them up and throw them aside; and wrenches or cold chisels to disconnect the tie rods from the rails.

The object of this invention is to greatly reduce the cost of removing the paving blocks, and of severing the tie rod connections between the rails.

The invention resides in the machine which is shown in the drawing, adapted to be drawn or pushed along the tracks, and provided with means which, as the car travels will completely loosen the pavement blocks, so that they may be picked up and thrown aside by the workmen, and will likewise cut the tie rods. So successfully does the machine shown perform the work for which it is organized, that it does the work which heretofore has required four hundred men working the same period of time.

In the drawings, Figure 1 is a side elevation of said invention. Fig. 2 is a plan view thereof, Figs. 3, 4 and 5 are respectively vertical sectional views through the plow beam

and its head in the plane indicated by lines 3-3, 4-4 and 5-5 respectively. Fig. 6 is a front elevation partly sectioned of the invention.

Referring to the parts by letters, A represents a heavily loaded car adapted to be pulled along the tracks C, C. Between these tracks the paving blocks B are laid on a loose layer of sand S, which covers, to the depth of an inch, more or less, the ties T, on which the rails are secured. A heavy beam D is hung freely on horizontal pivots d to the side frame members a , a , of the car, and projects forward therefrom. It may have a rearwardly projecting arm d^1 between which and the frame members a , a , of the car a beam K may be placed, of suitable thickness to properly limit the downward movement of the front end of said beam. When the machine is not in use the front end of said beam may be held above the pavement by a chain F engaging therewith, and with a forwardly projecting overhanging beam J carried by the car. This beam has at its front end a head D^1 which is considerably wider than the beam and is extended equal distances laterally on both sides of said beam. The head at its widest part is considerably narrower than the distance between rails, because it has been found that when so made it will serve the purpose for which it was intended quite as efficiently as if it were wider. This head is quite narrow at its front end, and said front end is beveled upward and downward so as to form a rather blunt edge d^2 which, when the head is in working position, as shown in Fig. 1, this front end will pass between the paving blocks B and the ties T without striking either. From this narrow front end, the head diverges laterally until it is of sufficient width, and then converges and is merged into the beam. There is formed upon this head an upwardly extended rib d^3 which is centrally placed and extends from a point adjacent to the front end rearward at a slight inclination upward to a point just behind the widest part of the head and from this point said rib is inclined more steeply upward. Two other V-shaped ribs d^4 are formed on the upper surface of the head on opposite sides of the central rib d^3 , which ribs d^4 incline upward slightly from their front ends rearward, and are preferably not parallel with the central rib.

Preparatory to using this machine it is necessary to manually remove enough paving blocks to leave a space into which the head may go and rest upon the sand layer 5 when the front end of the arm and the head are lowered to the position shown in Fig. 1. When, now, the car is drawn forward, this head, which has a smooth bottom surface, will slide on said layer S and will pass beneath the pavement blocks, and, being 10 slightly inclined upward from its front end, will lift the blocks from their seats. The central rib d^3 lifts the paving blocks in the middle above those on opposite sides thereof. The ribs d^4 will likewise impart a special upward movement to the blocks beneath which they pass. Although the head is considerably narrower than the distance between rails, it will nevertheless break the 15 connection between blocks which lie outside of it, but between the rails, as well as those beneath which it passes; and as a result the plow head, after passing, will leave the blocks between the rails, but so loosened 20 from their seats, and so completely separated from one another, that men following after can pick them up and throw them to one side. The head likewise passes beneath the tie rods T^1 and the central V-shaped rib 25 will engage the under surface of these tie rods as it comes to them, and will lift their middle part upward and will eventually break them, or pull one end or the other loose from the rail with which it was connected.

Having described my invention, I claim:

1. A railway paving plow comprising, in combination, a car, a plow beam pivoted to said car on a transverse horizontal axis and 40 extending forward therefrom, and having at its front end a head whose top surface is inclined upward from its front end rearward, and which is provided with an upwardly extended V-shaped rib which also 45 inclines upward from its front end rearward, and means for limiting the downward swinging movement of the front end of said

plow beam thereby determining the plane in which it will travel as the car is moved forward.

50

2. A railway pavement plow, comprising in combination a car, a plow beam pivoted to said car on a transverse horizontal axis and extended forward therefrom, said beam having at its front end a head which extends on opposite sides of said beam and has a narrow front end adapted to pass beneath the pavement blocks, and sides which diverge from said front end rearward and has a smooth bottom surface which adapts 55 it to slide on the sand layer in which the paving blocks are laid, and having its top surface inclined upward from its front end rearward, there being a rib formed on said head and extended rearward and onto said beam, the top surface of said rib being inclined upward toward the rear.

60

3. A railway pavement plow comprising in combination a car, a plow beam pivoted to said car on a transverse horizontal axis 70 and extended forward therefrom, said beam having at its front end a head which extends on opposite sides of said beam and has a narrow front end adapted to pass beneath the pavement blocks, and sides which 75 diverge from said front end rearward and has a smooth bottom surface which adapts it to slide on the sand layer in which the paving blocks are laid, and having its top surface inclined upward from its front end rearward, there being a rib formed on said head and extended rearward and onto said beam, the top surface of said rib being inclined upward toward the rear.

80

In testimony whereof, I hereunto affix my signature in the presence of two witnesses.

CHARLES H. CLARK.
